OF BROOKLYN, NEW YORK, A CORPORATION OF NEW YORK

MATRIX MAGAZINE

Application filed February 8, 1930. Serial No. 426,969.

The present invention relates to improvements in magazines for holding fonts of matrices for use in matrix setting and line casting machines, and more especially those of the class shown and described in U. S. Letters Patent No. 436,532 granted September 16, 1890 to O. Mergenthaler.

The matrix magazines as heretofore used generally in machines of this class comprise top and bottom plates of metal, usually brass, secured together by screws which extend transversely through the magazine and the top and bottom plates thereof and terminate in cross bars on the under side of the magazine, the top and bottom plates being spaced apart at intervals across the width of the magazine by vertical longitudinally extending partitions. The top and bottom plates of such magazines are formed on their inner faces with numerous grooves which provide channels to guide the respective matrices while descending by gravity from the upper toward the lower end of the magazine and to position the matrices for delivery from the magazine for the composition of matrix lines in a manner which is well understood in the art.

Magazines of this class as heretofore used generally are in themselves relatively heavy and when filled with fonts of matrices they are so heavy that great care must be used in lifting them to and from the machine and to and from storage racks usually provided in the composing room. Moreover, the weight of such magazines and their contained matrices is so great that considerable strength is required in transporting the magazines from place to place and damage sometimes occurs due to slipping of the magazine from the hands of the operator.

Such magazines have other objectionable features, especially that the top and bottom grooved plates are commonly made of metal and extend all the way to the upper end without reinforcement to prevent bending at the upper ends where the flared form of the grooves results in very thin exposed edges. Furthermore, the metal plates may become dented, resulting in a permanently deformed area about the dented portion and this dis-

turbs the spacing between the plates so that matrices will be hindered in passing freely through the magazine. Any bending or damage to the upper exposed ends of the plates or denting of the surface thereof is practically irreparable and a magazine thus damaged is useless.

The primary object of the present invention is to provide a novel and improved matrix magazine of this class which is relatively light in weight and yet possesses the requisite strength and rigidity, the lightness in weight of the magazine enabling it to be transported easily from one machine to another or to and from storage racks with safety against damage to the magazine and with greater facility than is possible with magazines of this class as heretofore constructed.

Another object of the invention is to provide novel means for reinforcing a matrix magazine having a non-metallic body portion wherein the reinforcement will interlock with and protect the exposed ends of the non-metallic portion against damage, or such metal reinforcing means may be constructed as an interlocking continuation of the non-metallic body portion capable of detachment for exchange or repair.

A further object of the invention is to construct a matrix magazine having a light-weight sheet or molded body portion, the materials of which will be resilient against denting or permanent deformation and adapted to receive reinforcement means.

To these and other ends, the invention consists in certain improvements and combinations and arrangements of parts all as will be hereinafter more fully described, the features of novelty being pointed out particularly in the claims at the end of the specification.

In the accompanying drawings:—

Fig. 1 is a perspective view of a matrix magazine constructed in accordance with the present invention;

Fig. 2 represents on an enlarged scale a section taken vertically through the magazine, the middle of the magazine being broken away;

Fig. 3 is a vertical sectional view through

the upper end of a matrix magazine constructed in accordance with another embodiment of the invention;

Fig. 4 is a fragmentary sectional view taken on the line 4—4 of Fig. 3;

Fig. 5 is an end view of the structure shown in Fig. 3; and

Fig. 6 is a fragmentary perspective view of a portion of one kind of non-metallic material which may be used in making the top and bottom plates.

The matrix magazine shown in the present instance is of the usual form or design commonly used in matrix setting and line casting machines of the class shown in the patent hereinbefore referred to, but in the improved construction provided by the present invention, the magazine comprises top and bottom plates which are preferably composed of suitable material which will not warp or wear unduly under the friction of the usual metal matrices sliding between them and will be lighter in weight than the brass top and bottom plates heretofore used generally in the construction of such magazines, and can be molded or in sheet form and will permit the usual manufacturing operations to be used in cutting the numerous guide grooves therein for the engagement of the lugs of the matrices therewith, it being preferable to make these top and bottom plates of a non-metallic material such as any of the solid phenol-formaldehyde condensation products known as bakelite, either with or without a canvas base *a* embedded therein and impregnated therewith as shown in Fig. 6 or fibrous material incorporated therewith, or of a vulcanized rubber such as hard rubber, vulcanite or ebonite, and either molded or in sheet form, all of which materials possess the above noted properties and, moreover, are moisture proof and are resilient and hence, not subject to bending, denting or other deformation, although these plates may, if desired, be composed of aluminum or any of its alloys which will be much lighter in weight than the brass top and bottom plates heretofore used generally. Preferably, and as shown in Figs. 1 and 2, these top and bottom plates designated 1 and 2 respectively, do not extend entirely to the upper and lower ends of the magazine but they terminate at the points 3, 4, 5 and 6 which are removed from the upper and lower ends of the magazine, and the ends of the top and bottom plates are mitered or bevelled so that they interlock and form close joints with correspondingly mitered or bevelled portions of removably fitted and replaceable reinforcing cross plates 7, 8, 9 and 10 which are composed of a relatively strong metal such as brass. The metal cross plates 7 and 9 at the upper end of the magazine are adapted to receive the matrices M from the distributor commonly used in machines of this class,

and the plates 8 and 10 are adapted to be positioned to deliver the matrices from the magazines to the usual assembler front commonly used in machines of this class, and the metal plate 10 may, as shown in the present instance, have the usual escapement mechanism 11 mounted thereon for controlling the delivery of the matrices from the magazine. By this construction, the matrix entrance and delivery ends of the magazines, being of metal, will be protected against damage by contact with the cooperating parts of the machine or from other objects, and the usual escapement mechanism for magazines of this class can be readily used. The top and bottom plates 1 and 2 have the usual matrix guiding grooves 1^a and 2^a cut or otherwise formed therein to receive the lugs or ears *m* on the corners of the matrices, and these grooves are continued in the metal plates 7, 9 and 10, and hence these fine channels or grooves will be more durable at the matrix entering and delivery ends of the magazines where the most wear ordinarily occurs and the most accuracy is required, and the removable fitting of the metal plates to the terminals of the plates 1 and 2 enables the metal terminal plates to be readily replaced when worn or damaged.

Ample strength and rigidity with minimum weight is afforded by extending rigid reinforcing cross bars 12 of metal transversely across the under side of the magazine, these bars being preferably of channel form in cross section as shown, and screws 13 are extended through the top and bottom plates 1 and 2 and also through the top and bottom metal plates 7 and 9 and 8 and 10 to rigidly bind such plates together, the screws opposite to the reinforcing bars 12 being threaded into or otherwise secured thereto so that these bars firmly clamp the under side of the magazine when such screws are tightened. The top and bottom plates of the magazine are maintained in proper spaced relation to accommodate the matrices so that they may slide freely between these plates, by partitions 14 which are preferably of thin metal and are interposed between the top and bottom plates at suitable intervals across the width of the magazine, and by side walls 15 which close the space between the top and bottom plates at the sides of the magazine, these side walls being preferably of metal and extending continuously from the upper to the lower end of the magazine and thereby stiffening the magazine longitudinally throughout its length. Preferably, two of the reinforcing bars 12 are located to underlie the ends 5 and 6 of the bottom magazine plate 2 so that these bars will provide a firm support on which the upper and lower ends of the bottom plate 2 and the joining ends of the metal bottom plates 9 and 10 may rest, thereby maintaining the joining ends of

these plates in alinement so that no shoulders will be produced at these joints which would obstruct or impede the sliding of the matrices through the magazine. Maintenance 5 of the upper and lower ends of the top plate 1 in alinement with the top metal plates 7 and 8 is insured by the mitered or bevelled formation of the meeting ends of these plates and by overlapping the plates 7 and 8 upon the ends of the top plate 1 as shown. The joint 6 at the lower end of the bottom plate 2 is preferably located more remote from the lower end of the magazine than the joint 4 for the top plate 1, thereby enabling the bottom metal plate 10 to be made of sufficient length to accommodate the escapement mechanism, and the consequent staggering of these joints in a direction longitudinally of the magazine increases its rigidity.

The objects of the invention may be accomplished in another form of the invention as shown in Figs. 3, 4 and 5. In Fig. 3 the top and bottom plates 1' and 2' of the magazine, which are preferably composed of any of the non-metallic materials hereinbefore mentioned, extend to the extreme top of the magazine and brass or other relatively strong metal reinforcing strips 7' and 9' are applied, preferably removably, to the upper ends of the respective plates to protect the non-metallic material from damage if struck, and these reinforcing strips are interlocked with the non-metallic plates 1' and 2' preferably by forming mitered joints 3' and 5' therebetween so that the non-metallic material will be held perfectly flat and the space across the entrance of the mouth of the magazine will be uniform across the entire width of the magazine. As an added protection against damage when the non-metallic material composing the top and bottom plates 1' and 2' extends to the extreme top of the magazine, additional thin or light metal strips *s* are inserted between the reinforcing cross strips 7' and 9' and the non-metallic material composing the top and bottom plates 1' and 2', and these strips *s* are formed over to cover the relatively sharp points of the walls between the matrix grooves 1^a and 2^a. It will be apparent from the fragmentary section shown in Fig. 4 that the matrix grooves of the non-metallic plates are widened out at the upper terminal end of the magazine, as is the usual practice, in order that the matrices may have freedom in entering their channels or grooves as they are distributed by the usual mechanism on a typographical machine. Fig. 5 is a further view looking into the entrance end of the magazine with the light metal protecting strips *s* formed with narrow lugs to fall exactly at the points of the walls between the matrix grooves or channels. The ends of the top and bottom plates in this form of the invention may be provided at the lower 65 end of the magazine with separate terminal

or reinforcing strips joined to the top and bottom plates and having matrix guiding grooves therein which are continuations of those in the top and bottom plates, as in Figs. 1 and 2.

While the invention is shown in the present instance as applied to a matrix magazine of one particular form or shape and in which the escapement mechanism is attached to or carried by the magazine, it will be obvious 70 that the invention is applicable to matrix magazines of other forms or shapes and to those wherein the escapement mechanism is not attached to the magazine but a cross bolt or bar is used for holding the matrices at the 75 delivery end of the magazine, and it will also be understood that the invention is applicable to small magazines such as those used on auxiliary or side unit attachments for matrix setting and line casting machines.

Since the major portion of the magazine as hereinbefore described is composed of a material substantially lighter in weight than the metal heretofore used generally in the construction of matrix magazines, the weight 80 of the magazine is substantially reduced so that the operations of applying and removing the magazines with respect to the matrix composing and line casting machines and of transporting the magazines from place to 85 place are facilitated and the danger of damage to the magazine during such handling or transportation is greatly reduced, and by making the top and bottom plates of a non-metallic material such as any of those hereinbefore referred to and which is resilient, denting thereof is resisted and prevented, so that obstruction to the passages of the matrices through the magazine, is avoided. By 90 reinforcing the upper and lower ends of the 95 magazine by strips of brass or other strong metal, damage to these ends of the magazine by contact thereof with portions of the machine in which the magazines are used or with other objects is substantially avoided. The 100 intermediate portions of the top and bottom plates are afforded requisite strength and rigidity by the underlying reinforcing bars and the relatively strong end plates to which 105 they are joined.

The terminal or reinforcing plates or strips, in either form of the invention shown, may be readily removed and replaced by others when worn or damaged, removal of the uppermost row of screws 13 in Figs. 1 and 2 110 releasing and enabling the upper plates 7 and 9 to be detached from the upper ends of the plates 1 and 2 and removal of the two lowermost rows of screws 13 releasing and 115 permitting removal of the lower plates 8 and 10; and removal of the screws 13^a releasing and permitting removal of the plates 7' and 9' in the form of the invention shown in Figs. 3, 4 and 5, so that interchanging of these 120 terminal plates, in either form of the invention, 125

with other similarly formed terminal plates may be readily accomplished.

I claim as my invention:—

- 5 1. A matrix magazine comprising top and bottom plates at at least one of its ends composed of relatively strong metal, and intermediate top and bottom plates composed of a different relatively lighter-weight material and reinforced by the first-mentioned plates.
- 10 2. A matrix magazine comprising top and bottom plates at its ends composed of relatively strong metal, and intermediate top and bottom plates composed of a different relatively lighter-weight material, the ends of 70 said intermediate plates being joined to said end plates, and the inner sides of said intermediate and end plates having matrix guiding grooves, the grooves in the end plates being continuations of those in the intermediate plates.
- 15 3. A matrix magazine comprising top and bottom plates spaced for the passage of matrices between them and composed of a non-metallic material, and reinforcing terminal 80 plates attached to the first-mentioned plates at at least one end of the magazine.
- 20 4. A matrix magazine comprising top and bottom plates composed of a non-metallic material, and metal reinforcing terminal 85 plates attached to the upper and lower ends of the first-mentioned plates.
- 25 5. A matrix magazine comprising top and bottom plates composed of a non-metallic material, and separate replaceable terminal 90 plates removably applied to the ends of the first-mentioned plates.
- 30 6. A matrix magazine comprising top and bottom plates composed of a non-metallic material and having matrix-guiding grooves 95 in their inner sides, and separate reinforcing plates applied to the upper ends of the first-mentioned plates and having matrix-guiding grooves therein which are continuations of the first-mentioned plates.
- 35 40 7. A matrix magazine comprising top and bottom plates composed of a resilient non-metallic material and grooved at their inner sides to guide the matrices between them, and metal reinforcing terminal plates interlocked with the ends of said non-metallic plates at at least one end of the magazine.
- 45 8. A matrix magazine comprising top and bottom plates composed of a resilient non-metallic material and grooved at their inner sides to guide the matrices between them, and metal terminal plates interlocked with the upper and lower ends of said non-metallic plates and having matrix-guiding grooves 100 therein which are continuations of the grooves in the non-metallic plates.
- 50 65 9. A matrix magazine comprising top and bottom plates composed of a resilient, light-weight non-metallic material, and replaceable metal reinforcing plates removably in-

terlocked with the upper and lower ends thereof.

10. A matrix magazine comprising top and bottom plates constituting the intermediate portion of the magazine, and top and bottom end plates joined to the ends of the first-mentioned plates, the joining ends of said plates being mitered, and means securing said plates together. 70

11. A matrix magazine comprising intermediate top and bottom plates, top and bottom end plates joined to the ends of said intermediate plates, and reinforcing members extending transversely beneath the magazine and underlying and supporting the 80 joining ends of the bottom intermediate and end plates. 75

12. A matrix magazine comprising intermediate top and bottom plates spaced apart for the passage of matrices between them, 85 transversely extending top and bottom end plates joining with the ends of the respective intermediate plates and forming continuations thereof, and means securing said intermediate and end plates together and to 90 one another. 95

13. A matrix magazine comprising top and bottom plates spaced apart for the passage of matrices between them and constituting the intermediate portion of the magazine, top and bottom end plates joined to the ends of the first-mentioned plates, the top end plates overlapping the respective ends of the first-mentioned top plate, reinforcing cross-bars 100 extending transversely beneath the magazine and underlying the joining ends of the first mentioned and end bottom plates, and means extending through the magazine and cooperating with said reinforcing bars to secure them in place. 105

14. A matrix magazine comprising top and bottom plates spaced apart for the passage of matrices between them and constituting the intermediate portion of the magazine, top and bottom end plates joined to the ends of the first-mentioned plates and constituting the ends of the magazine, and members interposed between and spacing said top and bottom plates and extending continuously throughout the length of the magazine. 110 115

In testimony whereof I have hereunto set my hand.

SAMUEL E. SPERRY.
